(57) **CLAIM**

The ornamental design for a display case, as shown and described.

DESCRIPTION

FIG. 1 is a front perspective view of a display case, showing my new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof; and,

FIG. 7 is a bottom plan view thereof.

The evenly spaced broken lines shown in the drawings depict portions of the display case that form no part of the claimed design.

The dash-dot-dash broken lines shown in the drawings denote the boundaries of the claim and form no part thereof. The front panel, having the dash-dot-dash broken lines thereon, is entirely transparent and thus objects behind the front panel can be seen therethrough.
